Patented May 1, 1917.

UNITED STATES PATENT OFFICE.

JACOB H. WEISBROD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

METALLIC CAR-WALL CONSTRUCTION.

1,224,816.

Specification of Letters Patent.

Patented May 1, 1917.

Application filed July 3, 1916. Serial No. 107,383.

To all whom it may concern:

Be it known that I, JACOB H. WEISBROD, a citizen of the United States, residing at the city of St. Louis, State of Missouri, have 5 invented a certain new and useful Improvement in Metallic Car-Wall Construction, of which the following is a full, clear, and exact description, such as will enable others skilled in the art to which it appertains to 10 make and use the same, reference being had to the accompanying drawings, forming part of this specification.

This invention relates to railway car construction, and specifically to a wall construction for freight cars.

The particular purpose of the invention is to provide a wall construction formed of sheet metal sections which are disposed one above another, and so shaped and conjoined 20 as to secure a desirable vertical stiffness and rigidity, particularly at the joints between the sections.

A further object is to provide a structure particularly adapted to use in the end wall 25 of freight cars by virtue of its ability to withstand cargo thrusts and support part of the roof load without being distorted.

Other objects of the particular construction will be obvious or pointed out herein- 30 after.

In the illustrative form shown in the accompanying drawings—

Figure 1 represents a front elevation of a car end of my improved construction;

Fig. 2, a horizontal section substantially 35 on line 2—2 of Fig. 1;

Fig. 3, a vertical section substantially on line 3—3 of Fig. 1;

Fig. 4, a similar vertical section of a 40 modified form;

Fig. 5, a cross section of said modified form such as would be taken substantially on line 5—5 of Fig. 4.

Reference being had to these illustrations 45 by the numerals applied thereto, it will be understood that numeral 1 indicates an upper panel of sheet metal, and numeral 2 indicates a similar lower panel. Both of these panels are provided with transversely 50 extending corrugations 4 which terminate adjacent the opposite margins of the panels or sections. The ends of the sections are flanged rearwardly to provide attaching

flanges 5 which are adapted to be secured to the corner posts or side wall portions of the 55 car superstructure. The upper margin of the upper section is arranged for attachment to the end plate 6 of the car frame, in any suitable fashion, such as by means of the Z-bar 7 riveted to the section and of size 60 and shape such as to form a pocket for the reception of the end plate. The fascia plate 8 may be applied on the exterior face of the upper section to provide a suitable weather closure. The lower margin of the 65 lower section may be flanged rearwardly, as at 9, to provide a flange adapted to receive and support the floor structure, and adjacent said flange the lower section may be attached to the car end sill 10, in any suitable 70 fashion, such as by means of the line of rivets 11 illustrated.

By reference to Fig. 3, it will be seen that whereas the corrugations 4 in both the upper and lower sections are of the same general 75 form and size, that, when the sections are assembled in the end structure, the upper section is disposed with the protuberant sides of the corrugations extending to the exterior of the car, whereas the lower section 80 2 is disposed with the protuberant sides of the corrugations extending to the interior of the car. This is the essential relationship of the sections, although it is immaterial as to which section has the corruga- 85 tions extending inwardly or outwardly. The disposal of the corrugations 4 and the sections is such that the corrugations are in alinement, and the width of the sections and length of the corrugations are such that the 90 sections overlap to a considerable extent with the result that the aligned corrugations in the different sections overlap at their re-entrant sides. Intermediate the two sections is disposed a plate 12 having its upper 95 margin turned over the upper margin of the lower section to provide an inwardly extending flange 14, and having its lower and outer margin directed outwardly to form a flange 15. Suitable fastenings 16 100 seated in the overlapping portions of the sections and in the joint member 12, secure the three members together. At its extremities, the joint member 12 is flanged rearwardly so as to embrace a portion of 105 the corner posts or side wall structure, and

is secured thereto by means of the bolts 17 which also secure the flanges 5 to the wall portions.

5 A wall constructed in this fashion will be possessed of great vertical stiffness, due to the stiffening influence of the corrugations 4 across the width of the sections, and due to the overlapping of said corrugations across the junction of the sections. By 10 virtue of this construction, continuous post-like members are formed in the wall structure itself, which members extend continuously from the upper to the lower portions of the wall, and enable the wall to carry 15 considerable vertical loads.

The inwardly directed flange 14 and the outwardly directed flange 15 of the joint member 12 coöperate with the sections and the corrugations to provide a continuous 20 transverse strengthening member at the junction line extending longitudinally of the sections. The inside flange 14 also forms a convenient seat for the nailing strip 18 which may be bolted thereto, and which 25 forms the conventional point of attachment and finish for the car lining 19.

In Figs. 4 and 5, the structure is modified to the extent of having the overlapping portions of the sections offset in the direction 30 of the protuberant sides of the corrugations, and in having the intermediate joint member 12^a shaped to conform to the offset form of the sections. By virtue of this construction, the crests of the corrugations are brought more nearly into vertical alinement with the wall portions of the other sections when the parts are assembled, with the result that the extreme innermost and the extreme outermost points on 40 the two sections are disposed respectively more nearly in the same planes, and the stiffness of the structure thereby somewhat increased.

It will be observed that the structure 45 above described provides a very stiff and rigid wall construction adapted not only to withstand local thrusts, but adapted also to effectively support vertical stresses without the use of posts.

50 I am aware that the devices illustrated and described are useful not only in end wall structures, but also in side wall structures, and that other changes, adaptations and modifications of the construction may 55 be made without departing from the scope and spirit of the invention indicated in the accompanying claims.

What I claim is:

1. In a railway car, a wall construction 60 including sheet metal panels one disposed above another and having portions overlapping and secured together, said panels being provided with corrugations extending angularly relative to the overlapping edges. 65 the corrugations in one panel overlapping

the corrugations in the other with their re-entrant sides together.

2. In a railway car, a wall construction including panels one disposed above another and having their adjacent marginal portions overlapped and secured together, said panels being provided with alined vertically extending corrugations extending into the overlapping portions, the corrugations in one panel protruding in a direction opposite to those in the other relative to the general plane of the wall. 70

3. In a railway car, a wall construction including sheet metal panels marginally conjoined and provided with corrugations, 80 extending angularly relative to the line of junction, said panels being secured together in such relationship that the corrugations in one protrude in a direction opposite to the direction of protrusion of corrugations 85 in the other and with the adjacent ends of the corrugations overlapped.

4. In a railway car, a wall construction including sheet metal panels one disposed above another, the uppermost and lowermost 90 margins of the panels being connected to car framing members and the adjacent margins of the sections being overlapped and secured together, said panels being provided with vertically extending corrugations extending 95 substantially to the uppermost and lowermost margins but terminating short thereof, the corrugations in one section overlapping the corrugations in the other to provide continuous vertical stiffening members 100 across the line of jointure.

5. In a railway car, a wall construction including sheet metal panels one disposed above another, said panels being formed with vertically extending corrugations, the 105 corrugations in one panel protruding inwardly of the wall structure, and the corrugations in the other panel protruding exteriorly of the wall, the adjacent margins of the panels being overlapped with the corrugations in alinement, and a flanged plate interposed between the overlapped portions 110 of the panels and extending longitudinally of the joint to form a stiffening member.

6. In a railway car, a wall structure including a pair of sheet metal panels one disposed above the other and provided with vertically extending corrugations, the adjacent marginal portions of the panels being overlapped; a flanged plate member interposed between the overlapped portions of the sections and secured thereto, said flanged member having a flange extending inwardly from the panels, and a nailing strip for the car lining secured to said flange. 115

7. In a railway car, a wall construction including a pair of sheet metal panels one disposed above the other and having their adjacent marginal portions overlapped, a stiffening member interposed between the 120 125

overlapped portions of the sections and secured thereto and extending longitudinally of the sections to form a stiffening reinforcement, said stiffening member including an inwardly extending flange, and a nailing strip for the car lining seated on said flange.

In testimony whereof I hereunto affix my

signature in the presence of two witnesses, this 27th day of June, 1916.

JACOB H. WEISBROD.
